(No Model.)

C. F. SPENCER.

CHANDELIER.

No. 245,264.

Patented Aug. 2, 1881.

UNITED STATES PATENT OFFICE.

CHARLES F. SPENCER, OF ROCHESTER, NEW YORK, ASSIGNOR TO HENRY S. BALLOU, OF SAME PLACE.

CHANDELIER.

SPECIFICATION forming part of Letters Patent No. 245,264, dated August 2, 1881.

Application filed December 30, 1880. (No model.)

To all whom it may concern:

Be it known that I, CHARLES F. SPENCER, of Rochester, Monroe county, New York, have invented a certain new and useful Improvement in Chandeliers and Drop-Light Fixtures; and I do hereby declare that the following is a full, clear, and exact description of the same, reference being had to the accompanying drawings, in which—

10 Figures 1, 2, and 3 are vertical sections of a chandelier or drop-fixture hanger, showing different forms of my improvement.

Ordinary chandelier or drop-fixture hangers are suspended from the ceiling loosely by a hook. This is objectionable for the reason that the chandelier swings or vibrates, especially when pressure is applied on one side in handling the fixture, or when one lamp is removed, thereby bringing an excess of weight 20 on one side.

It is the object of my invention to obviate this difficulty by providing means whereby the hanger may be attached stiff and fast to the ceiling, as hereinafter more fully described.

25 In the drawings, A shows the ordinary hanger or shaft which depends from the ceiling, and to which the lights are attached; and B represents the cap or center piece at the top of the hanger. a is the eye attached to the hanger; and b is the hook attached to the ceiling, the eye engaging with the hook and sustaining the parts.

In Fig. 1 a shank, c, is shown, forming a part of the eye, said shank having a thread, d, and 35 extending down through the solid top of the hanger, which forms a nut. At the bottom of the shank is a stop, f.

In Fig. 2 the shank c extends down through the whole length of the hanger, and below the 40 hanger a nut, g, screws upon its end.

In Fig. 3 the upper end of the hanger screws into the lower end of the cap or center piece, and the eye is permanently attached to the top of the hanger. When the hanger has been 45 hung upon the hook the cap or center piece, B, can be moved up, so as to abut firmly against the ceiling, by simply turning it up on

the screw, and in this condition the hanger is perfectly stiff and fast, and cannot swing or vibrate when the hand is applied to it, and it 50 will not move out of the vertical position when there is more weight on one side than on the other, which is a source of trouble in ordinary hanging chandeliers.

To disengage or detach the chandelier from its fastening, the cap or center piece is simply turned down on the screw till the eye can be lifted from the hook.

It has been common to use a fixed screw on top of the hanger and screw it into the ceiling. 60 It is almost impossible to drive it in straight, and it is frequently deflected, and sometimes broken, by striking knots or nails, in which case the chandelier stands sidewise, or cannot be sustained.

65 In this invention the joint of the hook and eye allows free movement, and the square top of the cap or center piece will always bring the hanger in the true vertical position when said cap strikes the ceiling.

70 Having thus described my invention, what I claim as new, and desire to secure by Letters Patent, is—

75 1. In a chandelier or drop-light fixture suspended by a hook and eye, the combination, with the hanger and cap-piece, of a screw or screw-thread, whereby the cap-piece can be forced up against the ceiling to stiffen the hanger after the hook and eye have been connected.

80 2. In a chandelier or drop-light fixture, the combination, with the hanger and cap-piece, of a screw-shank, c, passing down into or through the hanger and allowing the hanger to be tightened to the ceiling by moving up 85 upon the screw-shank, as herein shown and described.

In witness whereof I have hereunto signed my name in the presence of two subscribing witnesses.

CHAS. F. SPENCER.

Witnesses:

R. F. OSGOOD,
JACOB SPUHN.
